CARTON FORMING MACHINE

Morris A. Terry, Portage Township, Kalamazoo County, Mich., assignor, by mesne assignments, to Pre-O-Form Corporation, Warsaw, Ind., a corporation of Indiana
Filed Nov. 19, 1962, Ser. No. 238,401
18 Claims. (Cl. 93—44.1)

This application is a continuation-in-part of my patent application Serial No. 79,880, filed December 30, 1960, and entitled "Carton Forming Machine," now Patent No. 3,064,542, issued on November 20, 1962.

This invention relates in general to a carton forming machine and, more particularly, to a type thereof which is capable of receiving a plastic coated, substantially tubular carton blank and forming an end wall on one end of said tubular blank.

The advantages of and need for a relatively small machine for forming the bottom end wall in a plastic coated, tubular carton blank have been discussed in detail in my above-mentioned patent application Serial No. 79,880. In a continuing effort to improve upon the construction and performance of machines for preforming milk cartons, especially in the small dairy, it was found that a semiautomatic arrangement was often desirable in order to minimize the cost of the machine, the cost of maintenance and the space occupied by the machine. That is, many of the small dairies do not use enough milk cartons in a single day to warrant the investment and space required for a fully automatic preforming machine. By using a semiautomatic construction, it is practicable to reduce the number of stations through which the carton blank must move while the bottom wall is being formed therein. Accordingly, the size and cost of the machine are reduced proportionately.

It was also found that many of the small dairies would prefer to commence their own preforming operations on a very modest basis, even though cost was no object, in order to acquire preforming experience in a gradual manner and without upsetting the normal routine of the dairy. However, it was indicated that some of these dairies would desire a fully automatic machine after such experience had been acquired. Thus, the need has been present for a semiautomatic machine of modest cost and capacity, which is adapted for use by a small dairy, which can be used efficiently while obtaining preforming experience in a limited operation, and which can be converted with a minimum of cost into a substantially fully automatic machine when the need for same arises.

It was also found that many dairies desire an automatic preforming machine which is capable of prebreaking the upper end panels on the milk carton, even though they use a relatively small number of milk cartons. This is primarily due to the fact that they wish to be able to feed the preformed cartons directly from the preforming machine to an automatic machine for filling and sealing the cartons. Such a machine is the "Seal-O-Matic Senior" manufactured by Liquid Package Equipment Corporation of Woodstock, Illinois.

Accordingly, a primary object of this invention has been the provision of a semiautomatic and compact machine for receiving plastic coated, tubular carton blanks having end panels, and for automatically forming from said end panels an end wall which is held in a liquid-tight condition by the thermoplastic after heat and pressure are applied thereto by said machine.

A further object of this invention has been the provision of a relatively small machine, as aforesaid, for preforming a plurality of milk cartons from tubular and plastic coated carton blanks in rapid succession so that said cartons can be stored in their space saving, flattened

2

condition and quickly preformed in a minimum of space and time for immediate use.

5 A further object of this invention has been the provision of a preforming machine, as aforesaid, which can be efficiently operated by a minimum of personnel, which requires a minimum of cost for operation, which is easy to maintain and keep clean, and which completely satisfies the long standing need for a compact preforming machine of this type.

10 A further object of this invention has been the provision of a preforming machine, as aforesaid, which can be adapted for substantially fully automatic operation to erect a flattened carton blank and to form an end wall on the erected carton blank, such fully automatic operation being achieved by adding components to the basic, semiautomatic machine, either initially or as they are needed.

15 A further object of this invention has been the provision of a preforming machine, as aforesaid, which can be arranged by adding components to the basic assembly, to prebreak the top end panels on the preformed carton blank, either automatically or semiautomatically, so that said cartons can be transferred at once to a machine for filling and sealing the cartons.

20 Other objects and purposes of this invention will become apparent to persons familiar with this type of equipment upon reading the following specification and examining the accompanying drawings, in which:

For convenience in reference, the terms "upper," "lower" and words of similar import will have reference to the preforming machine and parts thereof as appearing in FIGURES 1 and 2. The term "front" will have reference to the side of the machine shown in FIGURE 2. The terms "inner," "outer" and derivatives thereof will have reference to the geometric center of the preforming machine and to parts thereof when they are being considered apart from the remainder of the machine.

General description

The objects and purposes of the invention, including those set forth above, have been met by providing a portable preforming machine for receiving tubular carton blanks which are plastic coated and which have integral closure panels at both ends of the tube. A plurality of mandrels are supported within the machine by a carrier, and drive mechanism moves the carrier so that the mandrels are advanced intermittently and unidirectionally along a closed path, such as a circle.

In one preferred embodiment, the flat carton blank is manually placed in a loading position directly above the path of movement of the mandrels and, at the same time, said carton blank is manually erected into its tubular form. Each mandrel is shaped so that it can slidably and snugly receive an erected carton blank, which is moved downwardly onto an upright mandrel disposed in the loading station. Additional stations are disposed in the machine preferably at uniform intervals along the path of movement of the mandrels and in axial alignment with said mandrels.

The loading station, which is the first station, includes a device for moving the carton blank downwardly onto a mandrel in the carton receiving station and, at the same time, breaking the bottom end panels at the upper end of the erected carton. The second station includes a heating mechanism for softening the thermoplastic coating on the upper bottom end panels. The third station includes guide means for moving the upper end panels downwardly toward horizontal positions and a pressure member for pressing the panels firmly against the upper end of the mandrel to produce a liquid-tight bottom wall. A fourth station is reserved for removing the preformed cartons either manually or automatically from their mandrels.

A modified machine includes automatic mechanisms for erecting the carton blanks and feeding them from a magazine into the carton loading position, and for removing the preformed cartons from the mandrels in the fourth station. The modified machine may include mechanism for prebreaking the panels at the other (top) ends of the cartons and for advancing such cartons from the preforming machine to a filling and sealing machine.

Detailed construction

The preforming machine 10 (FIGURES 1, 2 and 3), which has been selected to illustrate a preferred embodiment of the invention, is comprised of a frame structure 11 in which a carrier assembly 12 is supported for rotation around a substantially vertical axis. The carrier assembly includes a plurality of upright mandrels 17, which are arranged in a circle around said vertical axis. Drive mechanism 13 (FIGURE 2) is supported upon the frame structure 11 and is connected to the carrier assembly 12 for effecting step-by-step, unidirectional movement thereof.

A carton erecting mechanism 16 (FIGURE 1) is mounted upon the frame structure 11 directly above a loading station L in the circular path defined by the movement of the mandrels 17. The erecting mechanism is arranged for receiving tubular carton blank 18 and holding it in its fully erected and rectangular shape directly above said loading station. Prefbreaking and loading mechanism 19 is supported upon the frame structure 11 directly above and adjacent the loading station L for engaging an erected carton blank 18 and moving it downwardly onto a mandrel 17 in the loading position L while, at the same time, bending the panels 21 at the upper end of the erected carton blank 18 along the fold lines which separate the panels from the side walls of the preformed carton 22 (FIGURE 4).

Examples of cartons which may be handled in this type of machine are disclosed in patent applications Serial Nos. 111,028, filed May 18, 1961, now Patent No. 3, 118,586; 149,964, filed October 23, 1961; and 228,118, filed October 3, 1962. In this embodiment, the end panels 21 form the bottom wall on a preformed carton 22 (FIGURE 4).

A heating mechanism 23 (FIGURES 2, 6 and 17) is mounted upon the frame structure 11 near the heating station H (FIGURE 3) for softening the thermoplastic coating on the end panels 21 of an erected carton blank 18 (FIGURE 4) supported on a mandrel 17 located in the heating station H. A pressure mechanism 24 is located at, and primarily above, the pressure station P for the purpose of pressing the bent and heated end panels 21 against the upper end of the mandrel 17, upon which they are supported, to form the bottom wall on the carton 22. Said end panels 21 are held together by the thermoplastic coating thereon which is rendered adhesive by the heat applied to said panels while they are in the heating station H.

The preformed cartons 22 (FIGURE 4) are manually removed from the mandrel 17, in this particular embodiment, when said mandrels are disposed in the discharge station D. Thereafter, if desired, said preformed cartons 22 can be manually moved through the two stages of the top breaking mechanism 25.

The various, above-mentioned mechanisms are preferably operated by pressure fluid actuated devices, which are in turn controlled by an electrical circuit, such as that shown in FIGURE 41. For convenience of disclosure, the description of the machine 10 will follow generally the order in which the principal components thereof have been set forth in the foregoing paragraphs.

Frame structure

The frame structure 11 (FIGURES 1 and 2) is substantially rectangular and includes four, upright corner legs 26, 27, 28 and 29 which are secured to and support a substantially horizontal platform 32 located approximately midway between the upper and lower ends of the machine 10. The horizontal platform 32 includes a cover sheet 33 from which the skirt 34 extends downwardly around the upper portions of said legs. The platform 32, the cover sheet 33, the skirt 34, said legs and the other parts of the frame structure 11 are preferably fabricated from metal sheets and elements.

The frame structure 11 includes a plurality of upright elements 36 which are rigidly secured at their lower ends to the platform 32 and project upwardly therefrom substantially above the upper ends of the mandrels 17. An upper platform 37 is mounted upon the upper ends of the upright elements 36 and a hood 38 is removably supported on the upper ends of the upright elements 36 for the purpose of covering the structure which is supported upon the upper platform 37 and which is discussed hereinafter. The elements 36 are enclosed by side sheets 41 and 42 to form the left and right, vertical columns 39 and 40, respectively.

Carrier assembly

The carrier assembly 12 includes a circular, substan-

5 tially horizontal carrier disk 45 which is supported upon the turn table 46 of the indexing device 47, which is in turn supported upon the platform 32. The indexing device or table 47 is part of the drive mechanism 13 and, therefore, will be discussed hereinafter.

In this particular embodiment (FIGURE 4), there are eight mandrels 17 secured at uniform intervals around and upon the carrier disk 45, preferably at uniform radial distances from rotational axis of said disk 45. The four mandrels 17a are of appropriate size and shape to receive, snugly but slidably, an erected carton blank 18 of the conventional quart size. The four mandrels 17b are alternated with the mandrels 17a and they are of the proper size and shape to receive an erected carton of the half-gallon size. It follows that mandrels of different sizes and shapes, including mandrels suited to receive gallon cartons, can be supported upon the carrier disk 45 in a similar manner.

There are four stations (FIGURE 3), identified as 20 L, H, P and D, into and out of which each mandrel is 25 movable in a predetermined sequence. That is, where quart-size cartons are being preformed, each of the mandrels 17a will be located at one of said four stations, whenever the carrier disk 45 is at rest during the normal 30 operation of the machine. By appropriate adjustment of the rotational position of the carrier disk 45 with respect to and upon the turn table 46, the four quart-size mandrels 17a are replaced in said stations by the four half-gallon mandrels 17b. Thereafter, each movement of the carrier 35 disk 45 by the drive mechanism 13 will move the mandrels 17b from one station to the next.

Each mandrel 17 (FIGURES 4 and 6) may be fabricated in a manner and of materials generally similar to those disclosed in said patent application Serial No. 35 79,880. More specifically, each mandrel 17 is substantially rectangular in horizontal cross section and is vertically elongated. Each mandrel has a lengthwise recess 48 in the outer surface of each side wall thereof to minimize frictional engagement between said mandrels and the 40 erected carton blanks 18 disposed thereon. Furthermore, said recess 48 prevents the occurrence of a vacuum between the bottom wall of a preformed carton and the upper end of the mandrel when the preformed carton is removed therefrom.

Each mandrel 17 (FIGURE 6) has an upper cooling 45 chamber 51 and a lower collection chamber 52 which are connected by a central passageway 53. A vertical passageway 54 is provided in the side wall 56 of each mandrel 17 between the upper chamber 51 and a point adjacent the 50 lower end of said mandrel where said passageway opens to atmosphere. The upper chamber 51 is relatively small by comparison with the lower chamber 52 and the upper end of the passageway 53 may be provided with an upwardly extending projection 57 so that coolant disposed 55 within the upper chamber 51 must rise to a predetermined level before it can move downwardly through the passageway 53 into the lower chamber 52 and thence out through the passageway 58 which extends downwardly from the lower chamber 52 through the disk 45. Coolant can be 60 introduced into the lower end of the passageway 54, circulated through the mandrel 17 and collected from the lower end of the passageway 58 by means similar to those disclosed in said patent application Serial No. 79,880.

Drive mechanism

The drive mechanism 13 (FIGURES 2, 6 and 15) includes the indexing device 47 which, in this particular embodiment, may be a "Jackson Index Table," manufactured by the Jackson Fluid Power Company, Detroit, Michigan. Briefly, the indexing device or table 47 is comprised of a casing 61 having a sidewardly extending input shaft 62 (FIGURES 6 and 15) and an upwardly extending output shaft 63. The input shaft is connected by 70 the pulleys 64, 66 and the belt 67 to a motor 68 which is 75

secured to the frame structure 11. The input shaft 62 and output shaft 63 are interconnected by appropriate linkage, which is partially shown in FIGURES 6 and 15, whereby continuous rotation of the input shaft 62 is converted into intermittent rotation of the output shaft 63, hence of the turntable 46 secured thereto.

A connecting mechanism 69 (FIGURES 2 and 6) is secured upon the turntable 46 and adjustably connected to the carrier disk 45 for the purpose of rotating the disk 45 through a selected angle, such as 45 degrees, around its rotational axis with respect to the turntable 46 in order to place the mandrels 17b in the positions occupied by the mandrels 17a when such becomes desirable. This adjustment will normally be made when it becomes desirable to use the mandrels which are disposed between the stations L, H, P and D.

More specifically, the connecting mechanism 69 includes a spacing disk 72 (FIGURES 2 and 6) which is concentrically secured by means of bolts 73 upon the upper surface of the turntable 46. Said disk 72 has a centrally disposed, upwardly projecting shaft 74 which is threaded at its upward end and is concentric with the output shaft 63. The shaft 74 extends upwardly through a concentric opening 75 in the carrier disk 45 for engagement by a nut 76. A locating pin 77 projects upwardly from the upper surface of the spacing disk 72 for reception into any one of several pin openings 78 in the lower surface of the carrier disk 45. Said openings 78 are located at 45 degree intervals along a circular line concentric with the central axis of said disk 45. The 45 degree intervals are characteristic of this particular carrier assembly which has eight mandrels located at uniform intervals along a circle concentric with said carrier disk. Accordingly, this angular relationship would probably be different where the number of mandrels is different.

A table actuated switch 79 (FIGURES 2 and 41), is supported upon the left side of the casing 61 (FIGURE 2) so that its operator 80 is engageable by each of the four radially projecting and uniformly spaced switch actuators 81 for the purpose of closing the switch 79.

An anvil 82 is adjustably mounted upon a bracket 83 which is in turn supported upon the left side of the right column 40, adjacent and beneath the rightward edge of the carrier disk 45. Said anvil 82 is slidably engaged by the lower surface of the carrier disk 45 in a region directly below the pressure station P. Accordingly, the anvil 82 is arranged to counteract the downward urging of the carrier disk 45 by the pressure mechanism 24 when same is operated.

Erecting mechanism

The mechanism 16 (FIGURES 2, 3, 4, 5, 10 and 11) for erecting carton blanks 18 from their flat condition into their tubular condition is mounted upon and partially within the left column 39 of the frame structure 11 so that it extends directly over the loading station L. The mechanism 16, as particularly shown in FIGURES 2 and 3, includes three upright, substantially parallel corner members 86, 87 and 88 which are arranged to define a rectangle substantially identical with the cross-sectional shape of the carton 22 which is being preformed on the mandrel 17. The front corner member 86 is adjustably mounted upon the upper platform 37 by means of the bracket 89 for movement toward and away from the center of said rectangle. The corner members 87 and 88 are interconnected (FIGURE 11) by braces 92, and these combined parts are removably supported upon the platform 37 by means of a bracket 93 (FIGURE 10). Thus, the corner unit 94, including the corner members 87 and 88, can be replaced by another corner unit in which the corner members 87 and 88 are at a different distance from each other for the purpose of adapting the erecting mechanism 16 to a different carton size.

The erecting mechanism 16 (FIGURES 4, 5 and 10) has an associated safety device 96 to protect the hand 97

of the operator when he is inserting a carton blank into the erecting mechanism 16. The safety device 96 includes a switch 98 mounted on the right front corner of the left column 39 by means of the bracket 99. A manually operable switch operator 102 is hingedly supported upon the bracket 99 for movement around a substantially vertical axis. Said switch operator 102 includes a curved plate 103 which extends inwardly to the leftward edge of the rectangle defined by the erecting mechanism 16, hence adjacent the edge of a carton blank disposed within said erecting mechanism. The switch operator 102 has a finger 104 which extends away from the hinge pin 106 in the opposite direction from the plate 103 for engagement with the plunger 107 on said switch 98. A spring 108 urges the switch operator 102 into its FIGURE 4 position where the plunger 107 is depressed and the switch 98 is closed. The switch operator 102 is moved into its FIGURE 5 position by the operator's hand 97, thereby opening the switch 98 when a carton blank is placed within the erecting mechanism 16.

Prebreaking and loading mechanism

The loading mechanism 19 (FIGURES 2, 3, 10 and 11), which moves an erected carton from the erecting mechanism 16 onto a mandrel 17 disposed in the loading station L, includes a panel breaking or bending device 111 for bending the panels 21 at the upper end of the erected carton blank 18 after said device has moved the carton blank 18 onto a mandrel in said loading station. More specifically, the loading mechanism 19 includes a pressure fluid actuated cylinder 112 (FIGURE 11) which is mounted upon the frame structure 11 within the left column 39 in an upright position. The piston rod 113 of the cylinder 112 extends upwardly through a horizontal guide plate 114 secured to the upper end of said cylinder 112. The upper end of the piston rod 113 is rigidly secured to one end of a loading arm 116 which extends from the piston rod 113 rightwardly over and above the loading station L. A pair of guide rods 117 and 118 are rigidly secured to the loading arm 116 on opposite sides of and parallel with the piston rod 113 and said rods slidably extend through appropriate openings in the guide plate 114 for bracing and guiding the upward and downward movement of the piston rod 113. The loading arm 116 is movable through an opening 119 in the upper platform 37. The breaking device 111 includes a pair of spaced and downwardly diverging plates 122 and 123 which are secured to a support bar 124, which in turn is secured by the bolts 126 to the lower side of the arm 116 directly above the loading station L. The plates 122 and 123 may be arranged so that their lower edges move downwardly along and closely adjacent the inner surfaces of the corner members 86, 87 and 88 for the purpose of engaging the upper edges of the upper panels 21 on an erected carton blank 18 held within the erecting mechanism 16. The plates 122 and 123 are sloped so that they effect the desired amount of bending of the panels 21 with respect to the remainder of the carton blank 18.

The bar 124 (FIGURE 11) and loading arm 116 have aligned openings 127 and 127a, respectively, in which a rod 128 is vertically reciprocably disposed. A guide rod 129 is rigidly secured at its lower end to the loading arm 116 so that it extends upwardly adjacent to and parallel with the rod 128. A guide element 132 is rigidly secured to the rod 128 and has an opening 133 through which the guide rod 129 is slidably received. A guide element 134 is rigidly secured to the upper end of the guide rod 129 and has an opening 136 through which the rod 128 is slidably received. A spiral spring 137 is loosely sleeved upon the rod 128 between the guide elements 132 and 134 where said spring is continuously held, at least slightly, under compression. Accordingly, upward movement of the rod 128 with respect to the loading arm 116 is resiliently opposed by the spiral spring 137.

A pair of downwardly diverging, breaking elements 138

and 139 are rigidly secured to, and extend in substantially opposite directions from, the rod 128 near its lower end. The upper ends of the breaking elements 138 and 139 are spaced downwardly from the lower surfaces of the breaking plates 122 and 123 even when said elements are in their raised positions. A member 142 is secured to the lower end of the rod 128 for cushioning engagement of the rod with the upper end of a mandrel 17 in the loading station, when the breaking device 111 makes contact with the mandrel during the breaking of the panels 21.

Heating mechanism

The heating mechanism 23 (FIGURES 2, 3, 17 and 18) may be generally similar in construction and operation to the heating mechanism disclosed in application Serial No. 79,880. More specifically, the heating mechanism 23 includes a substantially horizontal support arm 146 which is pivotally supported at one end by means of the pivot bearing 147 upon the upper platform 37 for movement between the positions shown in FIGURES 3 and 6. Pivoting of the arm 146 may be effected by means including a pivot arm 148 which is connected at one end to the support arm 146 and at the other end to the piston rod 149 of the pressure fluid actuated cylinder 152, which is pivotally mounted by the pivot pin 153 upon the lower side of the upper platform 37. The pivot arm 148 is connected to the support arm 146 by a pivot shaft 154 which extends through the pivot bearing 147, which is supported upon the platform 37 by means of a mounting member 156 (FIGURE 3).

A pressure fluid actuated cylinder 157 (FIGURES 3 and 6) is mounted in an upright position upon the end of the arm 146 remote from the bearing 147, and the piston rod 158 of the cylinder 157 extends downwardly through an appropriate opening in the arm 146 for connection to a downwardly opening shell 159 having a heating element 162 mounted upon and extending around the interior surface of its side wall. The heating element 162 is connected in an appropriate manner to a source of electrical energy through the heat control 163 (FIGURE 2) having a manually operable rheostat 164 and/or automatic thermostat which are mounted within and/or upon the right column 40.

A switch 166 (FIGURE 2), having a switch arm 167, is mounted upon the support arm 146 so that the arm 167 is operated by a plate 168 secured to the piston rod 158. The normally open switch 166 is closed by engagement of its arm 167 with the plate 168 when the shell 159 is in its raised position and, therefore, out of the path of movement of the mandrels 17. A guide rod 169 is rigidly secured to the plate 168 and slidably extends upwardly through an appropriate guide opening through the support arm to guide and brace the movement of the piston rod 158.

Pressure mechanism

The pressure mechanism 24 (FIGURES 3, 4 and 6) includes a pair of guide bars 171 and 172 which are disposed between the heating station H and pressure station P. Said guide bars 171 and 172 are preferably in substantially the same horizontal plane which is disposed slightly above the upper surface of the mandrels 17 so that said mandrels can pass beneath said guide bars. The guide bars 171 and 172 converge toward the pressure station P and they are adjustably supported by means of the bracket 173 which is in turn mounted upon the right column 40. The guide bars 171 and 172 are spaced sufficiently from the heating station H to permit the shell 159 to move downwardly over the upper end of a mandrel 17 in the heating station without interference by said guide bars.

The pressure mechanism 24 (FIGURE 2) includes a pressure pads 174 which is removably supported upon a cooling head 176 which is in turn secured to the lower end of the piston rod 177 of the pressure fluid actuated

cylinder 178. The cooling head 176 has an internal cooling chamber (not shown) which can be connected by the conduits 181 and 182 to a convenient source of liquid coolant, not shown.

5 The lower substantially horizontal surface 183 (FIGURE 8) on the pressure pad 174 has a transverse step 184 which engages the panels 21, along a seam 185 formed in the bottom wall 188 by the overlap between two opposite panels, to facilitate the sealing therebetween. The downwardly projecting rings 186 are located at selected points 10 along the seams in the bottom wall 188 of the container 22 and thereby positively prevent seepage along such seams. More specifically, the diametrically opposite sides of each ring provide double sealing grooves in the bottom wall 188.

Top breaker

The top breaking mechanism 25 (FIGURES 1, 2 and 13) includes a pressure fluid operated cylinder 191, which is mounted in a vertical position upon the front wall 192 of the left column 39 so that the piston rod 193 thereof extends downwardly. The cylinder 191 is enclosed in the casing 194, and its piston rod 193 is secured at its lower end to a forwardly projecting T-shaped bar 196. The crosshead 197 of said bar 196 supports a pair of panel breaking devices 198 and 199 on the opposite ends thereof.

30 The panel breaking device 198 includes a rod 202 which is slidably received through a vertical opening 203 in the crosshead 197. A sleeve 204 slidably encircles the rod 202 and is rigidly secured to the crosshead 197 concentric with the opening 203 and extends upwardly therefrom. A guide rod 206 is rigidly secured to the crosshead 197 adjacent to and parallel with the rod 202. A guide element 207 is rigidly secured to the upper end of the guide rod 206 and has an opening 208 through which the rod 202 slidably extends. A guide element 209 is rigidly secured to the rod 202 between its ends and has an opening 212 through which the guide rod 206 is slidably received. A stop member 213 is secured to the upper end of the rod 202 to engage the upper guide element 207 and thereby limit downward movement of the rod 202 with respect to the crosshead 197.

35 A bracket 214 (FIGURES 3 and 13) is mounted upon the front wall 192 of the left column 39 below the upper end of the guide rod 206 so that it is engageable by the rearwardly extending, stop member 213 when the T-bar 196 is moved downwardly by the piston rod 193. Thus, the bracket 214 limits downward movement of the rod 202 with respect to the column 39. A spiral spring 216 loosely encircles the rod 202 between the guide elements 207 and 209 to continually urge the rod 202 upwardly into its FIGURE 13 position.

40 A substantially horizontal, panel bending plate or mandrel 217 is secured to the lower end of rod 202 for insertion into the open top end of a preformed carton 22 for the purpose of being positioned adjacent the upper fold line 218 (FIGURE 13) between the top panels 219 and side walls 222 of a preformed carton 22.

45 A pair of downwardly diverging, breaking fingers 223 and 224 (FIGURE 12) are rigidly secured to the lower side of the crosshead 197 adjacent the opening 203 there-in. The fingers 223 and 224 engage the gable end panels (FIGURE 14) of a preformed carton and thereby bend all four end panels inwardly toward the rod 202, as the T-bar 196 is moved downwardly. The spring 216 permits the piston rod 193 (FIGURE 12) to continue to move the breaking fingers 223 and 224 downwardly with respect to the carton 22 which they engage after the bending mandrel 217 has been stopped in its downward movement by stop member 213. This arrangement prevents engagement of the top panel 219, hence an improper bending before the mandrel 217 reaches the desired position adjacent the fold line 218.

50 75 The breaking device 199 (FIGURES 3 and 13) includes

a substantially vertical screw 226 which extends through a vertical opening 227 in the crosshead 197. The lower end of the screw 226 is rigidly secured to the upper end of a bifurcated member 228 having a pair of spaced and downwardly extending elements 229 and 230 defining a recess 233. A pair of widely and downwardly diverging plates 231 and 232 are secured, respectively, to the lower ends of the elements 229 and 230. The recess 233 is arranged to receive the rib on the top of a gabled carton, of the type disclosed in Patent No. 2,750,095. The divergence of the plates 231 and 232 is arranged to conform to the finished shape of the gabled top on said gabled carton. The screw 226 is engaged on opposite sides of the crosshead 197 by locking nuts 234 which adjustably hold the screw 226, hence the breaking device 199, in a selected vertical and rotational position with respect to the T-bar 196.

A carton supporting platform 236 is mounted upon the central platform 32 in front of the left column 39 and beneath the top breaking mechanism 23 to support simultaneously a pair of cartons 22 in the upright positions. As shown in FIGURE 12, the mandrel 217 extends slightly into the carton 22 when it is disposed upon the platform 236 thereby locating the carton with respect to the breaking device 198. Two pairs of upper and lower gripping arms 237 and 238, respectively, are secured to and extend forwardly from a back plate 239 mounted upon the platform 236 for the purpose of holding a preformed carton in proper position for engagement by the breaking device 199.

In this particular embodiment of the invention, the preformed carton 22 (FIGURE 4), having the bottom wall formed therein, is manually removed from the mandrel 17 in the discharge station D and thereafter manually inverted and mounted upon the platform 236 with the mandrel 217 extending into the upper end thereof. After the breaking device 198 performs its operation upon the top panels 219, the carton is then removed from its position beneath the breaking device 199 and is placed within the gripping arms 237 and 238 below the top breaking device 199. After the top breaking device 199 has performed its operation upon the top panels 219, the carton can then be placed in a filling and sealing machine, such as the one mentioned hereinabove.

Control mechanism

FIGURE 41 illustrates diagrammatically the electrical circuitry utilized in the machine 10 (FIGURE 3) for the purpose of co-ordinating the operation of loading mechanism 19, the heating mechanism 23, the pressure mechanism 24 and the top breaking mechanism 25 with the intermittent rotational movement of the carrier assembly 12. Specifically, the main start switch 242 is on the control panel 163 (FIGURE 2), which is mounted upon the right column 40. Closure of the switch 242 energizes the electrical system which is connected through the transformer 243 to a conventional source of 110-volt electrical potential. Accordingly, the motor 68 is energized through the normally closed terminals of the stop switch 245, and the operation of the indexing device 47 is commenced. That is, the table 46 is intermittently moved, at uniform intervals of time, through an angle of 90 degrees in this instance, whereby the mandrels 17 are shifted from one station to the next.

A normally open, momentary contact switch 79 is mounted upon the indexing device 47, so that said switch 79 is closed by the turntable 46 each time it is moved to advance the mandrels 17. Closure of the switch 79 energizes a solenoid valve 246 associated with the pressure cylinder 112 whereby the piston rod 113 is moved inwardly (downwardly as seen in FIGURE 11) to move a carton blank from within the erecting mechanism 16 (FIGURE 3) onto a mandrel 17 in the loading station L. When the piston rod 113 reaches the end of such stroke, it momentarily closes the "up" switch 247 whereby the solenoid

valve 246 reverses the flow of fluid to the cylinder 112 which raises the piston 113. When the piston rod 113 reaches the top of its stroke, it closes the timing start switch 248, which is of the momentary contact type, whereby the solenoid valve 249 is operated so that pressure fluid enters the pressure cylinder 152 and attempts to move the piston rod 149 outwardly.

A hydraulic check 252 (FIGURE 41) is coupled with the piston rod 149 to retard the operation of the pressure cylinder 152 in a predetermined amount. After a selected interval of time, the timing stop switch 256 is closed by the piston rod 254 of the pressure cylinder 253. This reverses solenoid valve 249 whereby the pressure cylinder 253 is returned to its initial position.

15 The "down" sides of the pressure cylinders 112, 157, 178 and 191 are all connected in parallel. That is, the solenoid valves 246, 257, 258 and 259 associated with the pressure cylinders 112, 157, 178 and 191, respectively, are all arranged so that said pressure cylinders are simultaneously caused to urge their pistons toward the "down" position. Also, the solenoid valves 257, 258 and 259 are connected in parallel to operate their respective pressure cylinders 157, 178 and 191, respectively, when the switch 256 is closed, whereby their pistons are moved upwardly, 25 substantially simultaneously.

The solenoid valve 262 is operated, when the momentary contact switch 253 is closed by the piston rod 158, so that pressure fluid will flow into the pressure cylinder 270 and urge extension of the piston rod 271. A hydraulic

30 timing check 264 is connected to the piston rod 271 for delaying its operation of the switch 260 until a selected period of time has elapsed. This time is governed by the time that can be safely elapsed before a carton disposed on a mandrel in the heating station H (FIGURE 3) would be damaged by the continued presence of the heating shell 159 directly thereabove. The "retraction" side of the solenoid 262 (FIGURE 41) is connected in series with a normally open, momentary contact switch 275 and the normally closed terminals 98a of the safety switch 98 to the transformer 243. The switch 275 is closed by an actuator 275a on the piston 271 before the switch 260 can be closed by the full extension of the piston 271.

When the switch 260 is closed, the solenoid 261 is operated so that the piston rod 149 is retracted by cylinder 152, thereby moving the heating mechanism 23 into its

45 FIGURE 3 position. Return of the heating mechanism 23 to its operating position of FIGURE 2 is effected by closing the manual switch 265. Switch 265 can also be used to move the heating mechanism 23 out of its operating position.

50 A switch 280 has two sets of terminals which are connected in parallel between the main start switch 242 and the safety switch 98. The switch 280 is open whenever the piston 149 is not fully extended or fully contracted, 55 hence whenever the heating system 23 is between its FIGURE 2 and FIGURE 3 positions. This prevents a cycling of the machine when the heating shell 159 could be jammed against a mandrel in the heating station H.

A second pair of terminals on switch 263 are connected 60 in series between the transformer 243 and the motor 68 to engage same and thereby initiate another step or cycle of operation. That is, the motor 68 causes the device 47 to index the table 46 through 90 degrees, whereby the switch 79 is closed and the various air cylinders are again operated.

Operation

The carton forming machine 10 (FIGURE 1) is ready for operation as soon as the electrical and pressure fluid connections are made from the machine to sources of supply. That is, the input leads on the transformer 243 (FIGURE 41) are connected to a convenient source of 110-volt potential and the hose 266 (FIGURE 1), which is connected to the various solenoid valves shown in FIGURE 41, is connected to a source of pressure fluid, such 75 as air. Normally, the rheostat 164 and/or its thermostat

(FIGURE 2) will be set at the proper temperature, as indicated by the gage 267, in order to produce the desired amount of heat in the shell 159. If the heating mechanism 23 is in its FIGURE 3 position, return thereof to the operation position of FIGURE 2 is effected by moving the switch 265 into its "in" position. Accordingly, operation of the machine will commence by closing the start switch 242.

The operator stands in front of the machine 10 with a supply of carton blanks either on a separate tray or upon the platform 32 in front of the right column 40. The operator of a co-ordinated filling and sealing machine, a portion of which is shown at 268 in FIGURE 29, can stand in front of the top breaking mechanism 25 and the operation of the machine 10 will then proceed as follows:

The first operator grasps a carton blank 18 (FIGURE 5), when it is in a substantially flat condition, and places one edge thereof against the corner member 87 while at the same time moving the curved plate 193 so that the switch 98 is opened. This prevents operation of the motor 63 when the switch 263 is closed and thereby prevents injury to the operator's hand while he is loading the carton blank into the erecting mechanism 16. By appropriate manipulation, the flat carton blank 18 is formed by the operator into a substantially diamond shape, as appearing in FIGURE 5, and thence into a rectangular shape so that the edge of the carton blank engaged by the operator's thumb will pass around, and be engaged by, the corner member 86, thereby holding the erected carton blank 18 in its rectangular, erected position.

As soon as the operator withdraws his hand from its FIGURE 5 position, the switch 98 is closed and, if the switch 280 (FIGURE 41) is closed, the motor 63 is energized to initiate the first step in the sequence of operation of the machine, which was started by the closing of the start switch 242. That is, the table 46 is turned through an angle of approximately 90 degrees, in this particular embodiment, during which the switch 79 is momentarily closed, thereby energizing the air motors 112, 157, 178 and 191. Operation of the air motor 270 is initiated when the switch 248 is closed by the return or upward stroke of the piston 113. Cylinder 270 is operated when the switch 263 is closed, but its operation is reversed if the operator loads a carton blank into the erecting mechanism 16 in the proper amount of time so that the switch 98a can close. The operation of the air motors 253 and 270 is retarded by the timing action of the hydraulic checks 252 and 264, respectively. However, the return operation of cylinder 270 by switch 275 is prompt so that the piston 271 is fully retracted when switch 263 is closed by the next cycle of operation.

If switch 98 is held open when switch 275 is closed, then the switch 260 will be closed by piston 271 after a predetermined period of time and the heating mechanism 23 will be promptly moved into its FIGURE 3 position by the cylinder 152. Movement of the heating mechanism 23 back into its operating position will be effected by the switch 265.

When the first step of operation commences, there will be no carton blanks in the heating station H or the pressure station P. Thus, only the loading mechanism 19 will perform an operation, which is the movement of a carton blank 18 from the erecting mechanism 16 onto a mandrel 17 disposed in the loading station L. After a predetermined period of time, controlled by the hydraulic check 252, the switch 256 is closed (FIGURE 41) whereby the "up" sides of the solenoid valves 257, 258 and 259 are opened so that the heating shell 159, pressure pad 174 and T-bar 196 (FIGURE 2) are simultaneously raised by the pressure cylinders 157, 178 and 191. Due to the special switch 247, which is closed by the piston rod 113 of the loading cylinder 112, the solenoid valve 246 is opened for "up" movement of the pressure cylinder 112 substantially in advance of the corresponding operation of the solenoid valves 257, 258 and 259. This gives the op-

erator a maximum amount of time in which to place a carton blank 18 into the erecting mechanism 16 before the next downward actuation of the loading mechanism 19. However, such upward movement of the loading mechanism does not affect the heating and pressure operations being performed at that time. This sequence of operations can be repeated and will be repeated normally at timed intervals controlled, as stated before, by the check 252.

10 Each time the power cylinder 157 raises its piston rod 158, it closes the switch 263 whereby the solenoid 262 is opened to effect a retraction of the piston rod 271 on the pressure cylinder 270. However, the check 264 retards movement of the piston rod 271 for a predetermined period of time, which substantially exceeds the normal interval between rotational movements of the turntable 46, whereby the switch 79 is closed and the electrical circuitry is energized to initiate another step of operation.

If there is a failure in the system at some point which 20 delays the normal operation of the machine beyond a safe period of time, the operator can manually close the switch 265 and thereby move the heating mechanism 23 into its FIGURE 3 position, where it will not damage a carton on the mandrel in the heating station H. Because the 25 switch 260 is connected through the switch 263, the air cylinder 152 cannot be operated automatically by closure of switch 260 unless the piston rod 158 is fully retracted and switch 263 is closed. This prevents outward movement of the heater shell 159 by the piston rod 158 whenever said shell is not in its raised position. Moreover, the shell 159 must be manually returned to its position above station H.

The loading mechanism 19 not only moves the carton blank 18 from the erecting mechanism 16 onto a mandrel 17 in the loading station L, but it also bends the panels 21 at the upper end of the carton blank 18 along their normal fold lines. Thus, when the carton blank 18 is subsequently moved into the heating station H and thence along the guide bars 171 and 172, said panels 21 will be first heated so that the coating thereon is rendered adhesive and said panels will thereafter be folded downwardly into substantially horizontal positions in which condition they will arrive into the pressure station P.

The pressure pad 174 will be moved downwardly by the 45 pressure cylinder 173 so that the bottom wall 183 will be formed in the carton 22. Subsequently, the preformed carton will be moved into the discharge station D where it is manually removed from the mandrel 17 and placed in position upon the platform 236 beneath the breaking device 198. The machine operator will normally perform this function while at the same time placing another carton blank into the erecting mechanism 16. The other operator will shift the carton from its position beneath the breaking device 198 to its position upon the platform 236 beneath 50 the breaking device 199, and thereafter will place the carton in a filling and sealing machine. Alternatively, the cartons may be merely stored for later use either with or without the tops thereof in their prebroken condition.

It will be noted that the breaking of the top panels 219 60 must be effected during two movements of the turntable because of the two breaking operations performed by the devices 198 and 199. However, it will be seen hereinafter that breaking of the top panels may be accomplished during each movement of the turntable 46 by reducing the 65 two step operation to a single step operation, without any material loss in time. The operation of the machine, as set forth in the foregoing paragraphs, may be continued substantially indefinitely and it makes no difference to the operation of the machine if its functions are performed 70 without cartons on the mandrels, at least for short periods of time. However, if it becomes desirable to stop the operation of the machine for any reason, this can be accomplished merely by closing the stop switch 245. Immediately, this action will momentarily energize the portion 75 of the circuit appearing in FIGURE 41 so that the loading

cylinder 112, the heating cylinder, 157, the pressure cylinder 178 and the breaking cylinder 191 are operated to raise their respective piston rods, regardless of the amount of time remaining in the period controlled by the timer 253. As soon as the piston rod 158 is raised by the pressure cylinder 157, the switch 263 will be closed and the timing will be commenced for movement of the shell 159 by the cylinder 152 into its safety position of FIGURE 3. Since the flow of energy to the motor 68 is interrupted through the switch 245, no further rotational movement of the table 46 can occur. Under normal circumstances, the start switch 242 and stop switch 245 will be coupled so closing of one opens the other.

Modified carrier assembly

The modified carrier assembly 12a (FIGURE 16) is, generally speaking, similar to the carrier assembly 12 appearing in FIGURE 4. Moreover, the rotational movement of the assembly 12a is effected for the purpose of performing its function, which is substantially the same as that discussed above with respect to the carrier assembly 12. However, the carrier assembly 12a is adapted to accommodate a greater variety of mandrels 272. That is, the carrier disk 273 supports quart mandrels 272a and half gallon mandrels 272b, which are rigidly secured upon the carrier disk 273 at uniform intervals therearound in substantially the same manner that the mandrels 17a and 17b are supported upon the carrier disk 45 (FIGURE 4). In addition, sleeve-type mandrels 272c are slidable over and upon the quart mandrels 272a, whereby the carrier assembly 12a can be quickly adapted for use in preforming gallon-size cartons.

Since the gallon mandrels 272c are merely sleeved upon the quart-size mandrels, a spring-backed pin 274 (FIGURES 17 and 20) is resiliently supported upon the gallon mandrel 272c, and said pin is slidably received through a pin opening 276 for removable reception into a pin recess 277 in the outer surface of the quart-size mandrel 272a upon which said gallon mandrel is sleeved. This prevents accidental removal of the gallon mandrel from its position upon the quart mandrel during the operation of the machine.

Because of the relatively large size of the gallon cartons 278, an additional breaking mechanism 279 (FIGURES 16, 18 and 19) is provided at the heating station H for the purpose of bending the upper panels 282 downwardly near the mandrel 272c prior to their engagement by the guide bars 283 and 284, which then complete this bending operation as the carton is being moved into the pressure station P. The guide bars 283 and 284 may be generally similar in structure and function to the guide bars 171 and 172 described above in connection with the carrier assembly 12.

The breaking mechanism 279 (FIGURES 16, 18 and 19) includes a pair of substantially horizontal and parallel breaking bars 286 and 287, which are secured to the lower ends of the L-shaped support members 288 and 289, respectively, FIGURE 17. The upper ends of the L-shaped support members 288 and 289 are rigidly secured to slides 291 and 292, respectively, which are held slidably in the guideways 293 and 294, respectively, for movement toward and away from each other. The guideways 293 and 294 are supported upon the lower surface of the upper platform 37a, which may be similar to the platform 37 in the machine 10.

A crank 297 (FIGURE 17) is rotatably supported upon said platform 37a and is connected by link bars 298 and 299 to the support members 288 and 289, respectively, whereby rotation of the crank 297 around its vertical axis effects movement of the breaking bars 286 and 287 toward and away from each other. A drive member 302 may be connected to the crank shaft 303 for the purpose of operating said crank 297 in a selected manner with respect to the movement of the heating shell 159a. That is, the breaking bars 286 and 287 would be moved inwardly to

5

engage and bend the carton panels 282 on the carton 278 when and only when the heating shell 159a is in a raised position. The breaking bars 286 and 287 would normally be held in such panel-engaging position until the mandrel supporting the carton had moved sidewardly to a point where said panels 282 would be engaged by the guide bars 283 and 284.

The particular breaking mechanism 279 does not permit sideward movement of the heating shell 159a, for the purpose of removing it from a position directly above the mandrel in case of a malfunction. Accordingly, automatic de-energization of the heating element within the shell 159a after a selected period of time would be provided as a safety feature. Moreover, the breaking mechanism 279 could be modified so that the shell 159a could be moved sidewardly into a safety position.

The alternate carrier assembly 306 (FIGURE 21) includes a carrier disk 307 which may be supported in a manner similar to the support of the carrier disk 45 (FIGURE 2). However, instead of mounting the mandrels 308 directly upon the disk 307, said mandrels are sleeved upon upright spindles 309, which are in turn rigidly secured at their lower ends to the carrier disk 307 at uniform intervals therearound and at uniform radial distances from the center of rotation of the carrier disk 307. A coolant passageway 311 may be provided in the spindles 309 for cooling thereof. Moreover, the mandrels 308, which may be in various sizes to fit various sizes of milk cartons, may be releasably held upon said spindles 309 by releasable locking means similar to that appearing in FIGURE 20.

It will be seen that the gallon-size mandrels 308c can either be sleeved directly over the quart-size mandrels 308a or they can be provided with a smaller opening to be sleeved upon the spindles 309. It will be obvious that the gallon mandrels 308c could also be sleeved upon the half-gallon mandrels 308b, merely by changing the size of the opening therein.

40

Automated top breaker

The top breaker mechanism 25a (FIGURES 22 to 28), inclusive, may be similar in form and operation with the top breaking mechanism 25 shown in FIGURE 2 and described above. However, the top breaking device 25a is disclosed herein as having breaking devices 198a and 199a which differ slightly from the corresponding breaking devices 198 and 199 in the top breaking mechanism 25. That is, the bending mandrel 217a at the bottom of the rod 202a has a notch 316 in its frontward edge for reasons appearing hereinafter. Also, the breaking fingers 223a and 224a are disclosed so that they extend frontwardly and rearwardly. However, this change is the result of the type of carton with which the structure is to be used and, therefore, does not result from the need for performing a new function.

The breaking device 199a is also rotated at 90 degrees in order to accommodate its position for operation upon a particular style of carton construction. The breaking device 199a includes a pair of spaced and substantially parallel fingers 317 and 318 which are secured to and extend downwardly from the fork member 228a through the recess 233a and between the plates 231a and 232a. The fingers 317 and 318 are arranged to engage the gable end panels just as the fingers 223a and 224a do.

The breaking device 198a is also rotated at 90 degrees in order to accommodate its position for operation upon a particular style of carton construction. The breaking device 198a includes a pair of spaced and substantially parallel fingers 317 and 318 which are secured to and extend downwardly from the fork member 228a through the recess 233a and between the plates 231a and 232a. The fingers 317 and 318 are arranged to engage the gable end panels just as the fingers 223a and 224a do.

65

A carton traversing mechanism 321 is mounted upon the front portion of the horizontal platform 32a in front of the left column 39a for receiving at its rightward end a preformed carton 22a and thereafter first moving said carton into and out of a position below the breaking device 198a and then into and out of a position beneath the breaking device 199a. Movement of a preformed carton 22a into the rightward end of the traversing mechanism may be accomplished manually in conjunction with the operation of a preforming machine 10, or it may be

accomplished by automatic mechanism, such as that disclosed hereinafter.

The traversing mechanism 321 (FIGURE 22) includes lower guide rails 322 and 323 which are supported in substantially horizontal positions upon the support bracket 327 which is in turn adjustably mounted upon the platform 32a by means of the block 328 and screw 329. The upper guide rail 324 is supported for frontwardly and rearwardly adjustment upon the upper end of a pair of vertical supports 332 and 333 which are in turn secured at their lower end upon the platform 32a. The rear upper guide rail 325 is supported upon the front wall 192a of the left column 39a. An upwardly and inwardly projecting stripping finger 336 is adjustably mounted upon the upper front guide rail 324 so that it projects into the notch 316 in the mandrel 217a when said mandrel is moving past the finger 336. The finger 336 is positioned so that it engages the upper edge of a carton 22a and prevents it from moving upwardly with the mandrel 217a when it is raised.

The traversing mechanism 321 includes a carton-advancing device 337 having three upwardly and frontwardly extending L-shaped elements 338, 339 and 340, which have substantially the same structure. The lower ends of said elements 338, 339 and 340 are rigidly secured to a base bar 343 which is pivotally supported at its opposite ends upon the piston rods 344 and 345 of a double-acting pressure cylinder 347. The base bar 343, as well as the advancing elements 338, 339 and 340 supported thereon, are simultaneously moved leftwardly or rightwardly by the pressure cylinder 347. The elements 338, 339 and 340 have upper and lower, frontwardly projecting fingers 348 and 349, respectively, which extend into the vertical zone defined by the upper guide rails 324 and 325 when said advancing elements are in their substantially upright positions. However, the base bar 343 can rotate around the common axis of the piston rods 344 and 345 so that the fingers 348 and 349 are moved out of said zone, whereby said advancing elements can be moved rightwardly or leftwardly by the pressure cylinder 347 without engaging cartons supported within said rails.

The pivoting motion of said advancing elements 338, 339 and 340, discussed in the foregoing paragraph, is accomplished by a bracket 352 (FIGURE 23) which is supported upon the upper end of a piston rod 353 of a power cylinder 354, which is mounted upon the frame structure 11a below the platform 32a. Accordingly, cartons 22a are advanced from right to left (FIGURE 22) along the traversing mechanism 321 by the advancing device 337, which first pivots rearwardly then moves rightwardly then pivots frontwardly and thereafter moves leftwardly. This sequence of movements is repeated at timed intervals by means such as the time-controlled devices shown in the circuitry of FIGURE 41.

As shown in FIGURE 27, the lower guide rails 322 and 323 can be moved upwardly, when the advancing device 337 is in its FIGURE 24 position, so that said guide rails will accommodate small cartons, such as those used to carry half-pints of liquid. Moreover, the traversing mechanism 321 can be adapted so that the leftward ends of said guide rails 322, 323, 324 and 325 will feed the cartons directly into the receiving end of a filling and sealing machine, such as the machine 268 discussed hereinabove.

Automated machine

The carton forming machine 361 (FIGURES 29 and 30) is provided in this embodiment with a frame structure 362, a carrier assembly 363, drive mechanism 364, loading mechanism 365, heating mechanism 366, mandrels 367, and pressure mechanism 368 which are substantially identical with their counterparts in the machine 10 (FIGURES 1 and 2). Accordingly, detailed descriptions of these assemblies are believed unnecessary, since reference can be made to the detailed disclosure of said counterparts which are set forth above. The mandrels

367 in the carrier assembly 363 are moved sequentially through a loading station L, a heating station H, a pressure station P and a discharge station D by said drive mechanism 364 in substantially the same manner as discussed hereinabove with respect to the carrier assembly 12.

5 The machine 361 is provided with a carton magazine 371, a carton extracting mechanism 372 and a carton discharge mechanism 373 which are not present in the machine 10. Moreover, the carton erecting mechanism 374 and the top breaking mechanism 376 differ somewhat from the corresponding mechanisms 16 and 25, respectively, in the machine 10. Accordingly, detailed description of these latter mechanisms will be given hereinafter. The discharge mechanism 373 is particularly designed for 10 operation in conjunction with a filling and sealing machine of the type referred to hereinabove as the "Seal-O-Matic Senior."

The carton magazine 371 may, broadly speaking, be 15 similar to the carton magazine disclosed in Patent No. 3,064,542. More specifically, said carton magazine 371 includes three upwardly opening, U-shaped members 377, 378 and 379 which are connected together in spaced alignment by a plurality of connecting rods 382. A pair of spaced and parallel inner rails 383 and 384 are secured to the webs 386 of said U-shaped members near the 20 central portions thereof. A carton feeding device 387 is supported upon and above said inner rails 383 and 384 for movement lengthwise thereof to urge a plurality of carton blanks 388 along said magazine toward the inner 25 end thereof. The feeding device 387 is comprised of a base block 389 having a pair of spaced and parallel axles 392 and 393 extending from both sides of said block and resting upon said rails 383 and 384. Rollers 394 and 395 are supported upon both ends of the axles 392 and 393, respectively, adjacent the rails 383 and 384.

30 A pair of holding rails 397 and 398 (FIGURES 30 and 37) are mounted upon the webs 386 on the opposite sides of and spaced from the inner rails 383 and 384, respectively. Flanges 399 and 400 on the holding rails 397 and 398, respectively, overlie the rollers 394 and 395 to prevent dislodgement of the feeding device 387 from 35 within its position in the carton magazine along the rails 383 and 384.

A feeding plate 403 (FIGURE 38) is secured to and 40 extends upwardly from the front end of the base block 389 substantially perpendicular to the lengthwise extent of the rails 383 and 384. Means, such as the spiral spring 404, is connected between the front end of the base block 389 and the front end of the magazine 371 whereby the feeding device 387 is continuously urged 45 toward the inner end of the carton magazine 371. The carton blanks 388 rest upon the upper edges of the holding rails 397 and 398, where they cannot interfere with the operation of the spring 404.

A handle 405 is mounted upon and extends upwardly 50 from the base block 389 for moving same outwardly away from the loading zone L when a new supply of carton blanks is being placed in the carton magazine. The front ends of the connecting rods 382, may be bent toward the central axis of the magazine to provide some 55 resistance to movement of the carton blanks 388 so that they will not fall out of the inner end of the magazine 371.

The inner end of the magazine 371 may be removably supported on the front face of the frame structure 362 adjacent to the left column 407 thereof. Spacers 408 and 409 (FIGURE 37) may be hung upon the inner side walls 411 and 412, respectively, of the carton magazine 371 to guide cartons of less width than the magazine 371.

The erecting mechanism 374 (FIGURE 30) is comprised of a left rear corner member 415 and front right corner member 416 which are supported upon the upper 60 platform 417 by brackets 418 and 419, respectively, which permit adjustment of said corner members 415 and 416 toward and away from each other. The corner member 416 includes a vertically elongated guide plate 422 which

extends frontwardly and rightwardly from the corner member 416 toward the right inner corner of the magazine 371.

The extracting mechanism 372 may be substantially similar in construction and function to the extracting mechanism disclosed in said Patent No. 3,064,542. That is, a plurality of vacuum cups 426 are mounted upon a substantially vertical bar 427 which is in turn engaged by and supported upon the piston rod 428 of a pressure cylinder 429 supported upon the upper platform 417. The vacuum cups 426 are movable between their retracted position of FIGURE 30 and a position adjacent to and engageable with the flat carton blank 388 at the inner end of the magazine 371. The inner carton blank 388 is removed by the extracting mechanism 372 through the broken line position 388a in FIGURE 30 wherein the guide plate 422 is engaged by one side of the carton blank 388 for the purpose of opening the same as it is moved into the erecting mechanism 374. Suitable controls are provided for reciprocating the vacuum cups 426 and controlling the vacuum pressure applied thereto.

After the extracting mechanism 372 has moved the carton blank 388 into the erecting mechanism 374, the loading mechanism 365 is actuated in a manner similar to that described in detail above with respect to the loading mechanism 19 for the purpose of moving the erected carton blank downwardly from the erecting mechanism 374 upon a mandrel 367 in the loading position L.

The discharge mechanism 373 (FIGURES 30, 31 and 32) is comprised of a lifting device 432 and a guiding device 433. The lifting device includes a pressure cylinder 434 having an upwardly projecting piston rod 436 and being mounted upon the front edge of the upper platform 417 adjacent to the discharge station D by means of the bracket 437. A guide rod 438 is secured at its lower end to the bracket 437 and extends upwardly therefrom adjacent to and parallel with the rod 436. A guide element 439 is secured to the upper end of the piston rod 436 and slidably engages the guide rod 438 for the purpose of minimizing lateral movement of the upper end of the piston rod 436. A vacuum cup supporting bracket 442 is secured to the guide element 439 and supports a pair of downwardly facing suction cups 443 which are vertically aligned with a mandrel 367 in the discharge station D (FIGURE 31). Accordingly, downward movement of the piston rod 436 by the cylinder 434 causes the suction cups 443 to engage the bottom wall of a carton mounted upon the mandrel in the discharge station. Subsequent upward movement of said piston rod 436 causes the suction cups 443 to raise the carton 446 into a position about as shown in broken lines in FIGURE 31.

A source of vacuum pressure, now shown, is connected to the suction cups 443 in a convenient manner. A spring element 444 is secured to the front edge of the platform 417 so that it extends forwardly into the path of the carton as it is moved upwardly by the suction cups 443. Thus, when the carton is moved upwardly, the spring 444 is flexed into its broken line position 444a. Subsequent release of the carton 446 from the suction cups 443 permits the flexed spring element 444 to flip the carton 446 rightwardly (as appearing in FIGURE 31) into the upper end of the chute housing 447.

The housing 447 (FIGURES 31), which has a front wall 448 and a pair of side walls 451 and 452, is mounted upon the frame structure 362 so that it extends down over the conveyor belt 453 to guide the movement of the carton 446 downwardly onto the conveyor belt in an upright position. A pair of baffles 454 and 456 are adjustably supported upon and between the side walls 451 and 452 for the purpose of controlling the downward movement of the carton 446 onto the conveyor belt 453. The adjustment of the baffles 454 and 456 is provided by the notched slots 457 and 458, for example, in the side wall 451. By appropriate movement of the baffles

454 and 456, they can be used for guiding cartons of different sizes and shapes. The operation of the pressure cylinder 434 can be coordinated with the operation of the other pressure cylinders, such as those operating the loading mechanism 365 and the heating mechanism 366.

The breaking mechanism 376, which is utilized to break the top panels 459 on the carton 446 (FIGURES 32 and 33), is comprised of a substantially rectangular outer casing 462 having side walls 463, a top wall 464 and a bottom wall 466. The casing 462 is removably supported upon the front wall of the left column 407 by means of the bracket 467. An elongated, substantially rectangular inner casing 468, which is open at the lower end thereof, extends downwardly through and is rigidly held within an opening 469 in the bottom wall 466. The lower edge of the inner casing of 468 is flared outwardly to facilitate the sliding reception of a carton 446 upwardly into said inner casing.

A pair of panel engaging members 472 and 473 (FIGURES 34 and 35) are connected together and slidably supported for vertical movement within the upper end of the inner casing 468 to engage the top panels 459 and bend them downwardly and inwardly along their normal fold lines to form the closure structure produced by said top panel 459. A pair of guide elements 474 and 475 are secured to and extend upwardly from the panel engaging member 472, for example, and project through appropriate openings in the top wall 478 of the inner casing 468.

30 Downward movement of the guide elements 474 and 475 (FIGURE 34), hence the panel engaging members 472 and 473, is limited by stop members 479 on the upper ends of the elements 474 and 475. A pair of spiral springs 482 and 483 encircle the guide elements 474 and 35 475 between the top wall 478 and the upper edge of the engaging member 472, thereby resiliently resisting upward movement of said engaging members. The panel engaging members 472 and 473 are arranged so that they properly engage and break the top panels 459 in the desired manner. The panel engaging member 472 has a pair of downwardly projecting elements 485 and 485a which have sloping and downwardly diverging plates 486 and 487, respectively, for engaging portions of said panels and facilitating the bending of such panels.

45 An air duct 488, which extends through the front wall of the left column 407 above the support bracket 442, communicates at one end with the interior of the outer casing 462 through an appropriate opening 489 through the top wall 464 of said outer casing. The air duct 488 is connected at its other end to a source 492 of negative and positive pressure. A plurality of perforations 490 are provided through the side walls 493 of the inner casing 468 immediately above the bottom wall 466 of the outer casing 462. Accordingly, when suction pressure 50 is applied through the duct 488 to the interior of the outer casing 462, the side walls of a carton 446 disposed within the inner casing 468 will be pulled snugly against the inner surfaces of the side walls 493. This action tends to prevent collapsing of the side walls 484 of the carton 446 adjacent the top panels 459 when said panels are being bent around their normal fold lines by the panel engaging members 472 and 473. A positive pressure can be applied through the duct 488 to urge the carton 446 downwardly from within the casing 468 after the top panels 459 thereof have been properly bent.

55 The conveyor belt 453 extends to a point directly below the rightward side of the breaking mechanism 376. A second conveyor belt 496 is spaced from and parallel with the first conveyor belt 453, and extends leftwardly from a point directly below the leftward side of the breaking mechanism 376. A platform 497 substantially fills the space between the conveyor belts 453 and 496 and is in substantially the same plane with the upper reaches of said belts. The platform 497 is mounted 60 upon an arm 498 which is in turn secured to the upper

end of the piston rod 499 of the pressure cylinder 502. A pair of guide rods 503 and 504 are secured to the arm 493 on opposite sides of the piston rod 499 and are slidably received through a guide plate 506 mounted upon the apparatus of the pressure cylinder 502 for the purpose of minimizing lateral deflection of the piston rod 499 as it is moved upwardly. The carton 446 is moved by the conveyor belt 453 onto the platform 497 and thereafter moved upwardly into the inner casing 468 for the purpose of breaking the top panels 459.

After the breaking operation has been completed and the carton has been moved downwardly into its solid line position of FIGURE 32 on the platform 497, the next carton which is moved along the conveyor belt 453 will engage the first mentioned carton, which is resting upon the platform 497, and move said first carton onto the conveyor belt 496, whereby said first carton will be moved leftwardly. The second carton will not rest on the platform 497 for top breaking thereof.

A suitable microswitch 507 may be provided along the conveyor belt 453 to initiate actuation of the pressure cylinder 502 when a carton arrives at the proper location upon the platform 497. Additional microswitches 508 and 509 may be mounted within the frame structure 362 adjacent to one of the guide rods 503 and 504 for operation by means thereon to control the movement of pressure fluid from the source 492 through the duct 488.

Alternate carton discharge mechanism

An alternate discharge mechanism 512 (FIGURES 39 and 40) may be used on the the machine 361 (FIGURE 29) in place of the discharge mechanism 373. The alternate discharge mechanism 512 includes a pair of spaced and parallel pivot arms 513 and 514 which are pivotally supported near their upper ends upon a horizontal pivot shaft 516 which is in turn supported in the bearings 517 and 518 mounted upon the front edge of the upper platform 417a. A recess 519 is provided in the leading edge of the platform 417a to receive the depending portions of the pivot arms 513 and 514, and to permit relatively free swinging action thereof. A horizontal, lower axle 522 is mounted upon the lower end of the pivot arms 513 and 514 parallel with the pivot shaft 516 to support a pair of resiliently flexible rollers 523 and 524 on opposite ends thereof. Said rollers 523 and 524 are located so that they engage each mandrel 367a near the upper end thereof when said mandrel is moved by its carrier assembly 363a into the discharge station D, which is adjacent said alternate discharge mechanism.

A pair of sprockets 526 and 527 are mounted upon the pivot shaft 516 and lower axle 522, respectively, between the pivot arms 513 and 514. An endless chain 528 encircles the sprockets 526 and 527. A motor 529 is mounted upon the platform 417a so that its shaft 530 is spaced from and substantially parallel with the pivot shaft 516. Sprockets 533 and 534 are mounted respectively upon the motor shaft 530 and the pivot shaft 516, and they are interconnected by endless chain 535. Accordingly, operation of the motor 529 effects a rotation of the rollers 523 and 524 in a counterclockwise direction as appearing in FIGURE 39. If the rollers 523 and 524 are moved into their broken line position of FIGURE 39 when they are rotating, a carton 446a mounted upon the mandrel 367a will be moved upwardly by said rollers with respect to said mandrel 367a.

A pressure cylinder 563 is supported in a substantially horizontal position by the bracket 537 upon the upper platform 417a and the outer end of the piston rod 538 of said cylinder 563 is pivotally secured by means of the pivot rod 539 to the upper ends of the pivot arms 513 and 514. Accordingly, by appropriate actuation of the pressure cylinder 563, the pivot arms 513 and 514 are pivoted to cause the rollers to move into their broken line positions of FIGURE 39.

A pair of spaced, parallel and coaxial disks 542 and

543 are rotatably supported by the bracket 544 adjacent to the discharge station D and upon the frame structure 362a. Said disks are adjustably spaced from each other a distance about equal to the cross-sectional dimension of the carton 446a being preformed on the mandrel 367a. The disks 542 and 543 are disposed directly above and close to the upper end of the mandrel 367a so that the carton 446a is moved upwardly between and thereby gripped by said disks 542 and 543 when said carton is moved upwardly by the rollers 523 and 524. A power-driven means may be provided for positively rotating the disks 542 and 543 or, alternatively, they may rely for their rotation upon the movement imparted thereto by a carton 446a after it is moved upwardly into and between the disks 542 and 543 by the rollers 523 and 524.

A stripping plate 546 extends upwardly between the disks 542 and 543 from a point adjacent the conveyor belt 453a, where it is mounted upon the conveyor frame 547. Thus, when a carton 446a reaches the position 446b, the bottom end of the carton is engaged by the stripping plate 546 and guided out of the disks 542 and 543 downwardly onto the conveyor belt 453a.

Alternate automated top breaker

25 The modified machine 555 (FIGURE 42) includes a frame structure 556, a carrier assembly 557, a carton magazine 558 and a discharge mechanism 559 which may be substantially identical with the corresponding components of the machine 361 (FIGURE 29). In fact, the 30 modified machine 555 may be substantially identical with machine 361, except for the carton conveying mechanism 562, the top breaking mechanism 563 and parts directly associated therewith.

The carton conveying mechanism 562 (FIGURES 42, 35 45, 46 and 47) is comprised of an elongated, and substantially rectangular casing 564 having a front wall 566, a rear wall 567 and a top wall 568. The conveying mechanism 562 is supported along its rear side by means of brackets 569 which are connected between the rear wall 467 and the platform 572 on the frame structure 556. A pair of legs 573 are secured to and extend downwardly from the casing 564 adjacent the front wall 566. A skirt 571 is secured to and extends downwardly from the front wall 566. The casing 564 (FIGURE 42) extends from 45 a point rightwardly of the discharge mechanism 559 to a point beyond the leftward side of the frame 556.

A guide plate 574 (FIGURES 46 and 47) is disposed in a substantially horizontal position within the chamber 576 defined by the walls of the casing 564. The guide plate is pivotally secured near its leftward and rightward ends to the pivot links 577 and 578, respectively, which are pivotally mounted by means of the pivot pins 579 and 580, respectively, upon and between the side walls 566 and 567. A slide plate 582 is slidably supported upon the guide plate 574 for movement lengthwise thereof and lengthwise of the casing 564 within the chamber 576. The pivot links 577 and 578 permit upward and downward movement of the guide plate 574 and slide plate 582 toward and away from their broken line 60 positions in FIGURE 47 snugly adjacent the lower surface of the top wall 568. Downward movement of the guide plate 574 is positively limited by a crossbar 583 which extends transversely through the chamber 576 and through a pair of vertical slots 584 and 585 in the front 65 and rear walls 566 and 567, respectively. The crossbar 583 is movable vertically within the limits of the slots 584 and 585.

A plurality of uniformly spaced fingers 587 (FIGURE 47) are rigidly secured to the slide plate 582 substantially 70 along the center line thereof and extend upwardly a uniform distance therefrom. Preferably, the vertical extent of the fingers 587 is such that their upper ends are adjacent the lower surface 568 when the guide plate 574 is in its lowered, solid line position of FIGURE 47. When 75 the guide plate 574 is raised, as indicated in broken lines

at 574a in FIGURE 47, then the fingers 587 assume their broken line positions 587a. The spacing between the fingers 587 is somewhat greater than the cross-sectional dimension of the largest preformer carton 588 which is to be handled by the carton conveying mechanism 562.

A lead finger 589 (FIGURE 47) is mounted upon the leftward end of the slide plate 582 in alignment with the fingers 587 and at a distance from the nearest finger 587 approximately equal to twice the distance between two fingers 587. A pivot arm 592 is pivotally supported at its left end upon the slide plate 582 by a pivot pin 593 located adjacent the right side of the lead finger 589. Said arm 592 extends rightwardly along said slide plate 582 and has an upright finger 594 integral with its rightward end. A leaf spring 596 is rigidly mounted near its leftward end upon the slide plate 582 so that it extends rightwardly beneath the pivot arm 592. The rightward end of the leaf spring 596 is secured to the pivot arm 592 and tends to hold same in alignment with the fingers 587 and 589. When the pivot arm 592 is in this position, the pin 594 is disposed approximately midway between the finger 589 and the leftwardmost finger 587. The upward extent of the fingers 589 and 594 is preferably approximately the same from the slide plate 582 as the upward extent of the fingers 587.

A pressure cylinder 597 (FIGURE 47) is pivotally mounted near its rightward end by means of the bracket 598 upon the casing 564 within the rightward end of the chamber 576. The bracket 598 supports the pressure cylinder 597 for pivotal movement with respect thereto around a substantially horizontal axis transverse of the chamber 576. The piston 599 of the pressure cylinder 597 is pivotally connected at its leftward end to a bracket 602 which extends through a lengthwise slot 603 in the guide plate 574 and is rigidly secured to the bottom of the slide plate 582. The slot 603 is substantially longer than the stroke of the piston 599 which stroke is approximately equal to the centerline distance between a pair of adjacent fingers 587.

A switch 606 is mounted upon and within the casing 564 for operation by the crossbar 583, hence by movement of the top breaking mechanism 563, as discussed hereinafter. The switch 606 is connected to and operates a solenoid valve 607 which controls the operation of the pressure cylinder 597. More specifically, closure of the switch 606 by the crossbar 583 causes the pressure cylinder 597 to retract its piston 599 whereby the slide plate 582 is moved rightwardly. Opening of the switch 606 causes the pressure cylinder 597 to extend its piston 599 whereby the slide plate 582 is moved leftwardly. The slide plate 582 will be in its solid line position of FIGURE 47 when it is moved rightwardly and it will be in its broken line position 582a when moved leftwardly.

The top wall 568 (FIGURE 45) has an elongated slot 611 which extends from near one end thereof to a point near the other end thereof. Said slot 611 is located so that all of the fingers 587, 589, and 594 can extend upwardly therethrough at the same time regardless of the location of the slide plate 582 along the guide plate 574. An arcuate, spur slot 612 is provided in the top wall 568 near the leftward end thereof so that it extends rearwardly and leftwardly out of the slot 611. The mouth 624 of the spur slot 612 is spaced from the leftward end of the slot 611 a distance slightly greater than the center line distance between the lead finger 589 and swinging finger 594, for reasons appearing hereinafter.

A pair of guide rails 613 and 614 are supported upon the top wall 568 adjacent the rear and front edges thereof, respectively, and project upwardly therefrom for the purpose of guiding a preformed carton 588 (FIGURE 45) lengthwise along the top wall 568. The guide rails 613 and 614 have elongated slots 616 and 617 in their opposing faces and near their rightward ends to receive the lower ends of the baffles 618 and 619 which project downwardly from within the lower end of the housing 622 of the discharge mechanism 559.

The guide rail 614 has a projection 623 on its inner surface which is engageable by the leading edge of a preformed carton 588 being moved along and between the guide rails 613 and 614 by the swinging pin 594. The projection 623 is intentionally located so that it will be engaged by the said carton when said swinging finger 594 is directly opposite the mouth 624 of the spur slot 612. Accordingly, the swinging finger 594 can and will move into the spur slot 612 as it twists the carton and at the same time slides along the trailing surface thereof, as appearing in FIGURE 45. The opposite face of the rear guide rail 613 has an elongated, lengthwise recess 626 which receives the corner of the carton 588 as the carton is rotated around its vertical axis by the swinging pin 594 moving along the spur slot 612.

The carton is rotated by the structure disclosed in the foregoing paragraph through an angle of 90 degrees so that the preformed carton can be moved from the discharge mechanism 559 by the converging mechanism directly into a filling and sealing machine. The position in which the carton blank is placed upon the mandrels of the carrier assembly 557 is determined by the way in which the bottom wall of the carton is formed. This arrangement varies in different types of cartons.

When a carton blank is formed so that the rotation thereof around the vertical axis is not required, then the guide rails 613 and 614 can be rotated around their lengthwise axes through an angle of 180 degrees so that their outer, smooth edges are facing each other.

The top breaking mechanisms 563 includes a vertically reciprocable head support 631 mounted upon the casing 564 approximately midway between the discharge mechanism 559 and the leftward end of said casing 564. The head support 631 includes front and rear support members 632 and 633, respectively, which are substantially parallel and which are connected together near the lower ends and below the casing 564 by the connecting plate 634. The support member 632 (FIGURE 45) is vertically, slidably supported upon the front surface of the front wall 566 by the vertical guides 637 and 647. The support member 633 is vertically, slidably supported upon the rear surface of the rear wall 567 by the vertical guides 638 and 639.

The support members 632 and 633 (FIGURE 46) have centrally located, vertically elongated slots 642 and 643, respectively, which are substantially longer than and in registry with the slots 584 and 585, respectively. The opposite ends of the crossbar 583 extend respectively into the vertical slots 642 and 643 where said ends of said crossbar are engageable by the lower ends of said slots 642 and 643 for the purpose of raising said crossbar 583. That is, the crossbar 583 is moved to the upper ends of the slots 584 and 585 during the last part of the upward movement of the head support 631, whereby said crossbar 583 moves the guide plate 574 into its broken line position 574a of FIGURE 47. Cover plates 644 and 645 are mounted upon the front and rear surfaces, respectively, of the support members 632 and 633 so that they cover remote sides of the slots 642 and 643.

The upper end of the piston 647 of the pressure cylinder 648 (FIGURE 46) is rigidly secured to the connecting plate 634 whereby the head support 631 is vertically reciprocated.

A breaking head 651 (FIGURES 46, 49 and 50) is adjustably and removably supported upon and between the upper ends of the support members 632 and 633. The breaking head 651 includes a pair of separable head halves 652 and 653 which are substantially mirror images of each other and, when together, define a tubular structure open at its upper and lower ends, and having a substantially rectangular cross section. A cap 654 is secured to the upper ends of the head halves 652 and 653. A pair of bosses 666 and 667 are integral with the head halves 652 and 653, respectively, and project inwardly therefrom near to but spaced upwardly from the lower ends of said

head halves to define upper and lower chambers 668 and 669 within the breaking head 651. The head halves 652 and 653 are flared outwardly adjacent the lower end of the lower chamber 669 to facilitate movement of the upper end panels 671 (FIGURE 42) of a preformed carton 588 into the lower chamber. The internal dimensions of the lower chamber 669, transversely thereof, are substantially the same as the external dimensions of the upper end panels 671 of an unbroken, preformed carton 588.

The cap member 654 has a central, vertical opening 672 through which a rod 673 is slidably received. The upper end of the rod 673 is threaded for engagement by an adjustment nut 674. A pair of flat, downwardly extending plates 676 and 677 are rigidly secured to and extend downwardly from the lower end of the rod 673 so that they lie in substantially vertical planes intersecting each other perpendicularly substantially along a line concentric with the lengthwise axis of the rod 673. As shown in FIGURES 46 and 49, the lower edges of the bending plates 676 and 677 are recessed to define a pair of downwardly diverging edge portions which are engageable with the upper end panels 671 of a carton 588 for breaking same along the fold lines thereof. Vertical grooves 678 and 679 are provided in opposing side walls of the head halves 652 and 653, respectively, so that they extend upwardly through the bosses 666 and 667 for slidably receiving and guiding the opposite vertical edges of the bending plate 676. Similar grooves 681 and 682 are provided within the breaking head 651 along the intersections of the head halves 652 and 653 for receiving and guiding the opposite vertical edges of the bending plate 677. The bosses 666 and 667 are spaced from each other a distance sufficient to permit the rib on top of a gabled carton to extend upwardly therebetween when a breaking operation is being performed upon the end panel 671.

A spiral spring 683 (FIGURES 46 and 49) encircles the rod 673 between the cap member 654 and the upper edge of the bending plate 676 for the purpose of resiliently resisting upward movement of the bending plates 676 and 677 during the breaking of the upper end panels 671. This arrangement tends to assure a proper bending of the upper end panels 671 with respect to the remainder of the carton 588 during the breaking operation.

Because the upper chamber 668 is closed at its upper end, abrupt relative movement of an upwardly opening, preformed carton 588 into the lower end of the lower chamber 669 tends to compress the air within the breaking head 651 and within the carton 588. This produces an outward pressure against the side walls of the preformed carton 588 which forces said carton walls against the inner surfaces of the breaking head defining the upper and lower chambers. Thus, a good clean and sharp folding or bending of the upper end panels 671 is achieved along the fold line separating said panels from the remainder of the carton. Under normal circumstances, one size of breaking head 651 can be used to form quart, pint and half-pint cartons and heads of different sizes would be used to form half-gallon and gallon cartons.

The upper ends of the support members 632 and 633 (FIGURE 42) have vertical, aligned slots 684 and 685, respectively, which open through the upper edges of their respective support members. The slots 684 and 685 have sidewardly extending spurs 687 and 688, respectively. Recesses 689 and 690 are provided in the rightward edges of the support members 632 and 633, respectively so that they correspond in vertical positions with the spurs 687 and 688, respectively. Studs 692 and 693 extend from the front and rear sides, respectively, of the breaking head 651 in such positions that they are receivable into the spurs 687, 688 and recesses 689, 690 for the purpose of positively positioning the breaking head 651 with respect to the head support 631. Nuts 695 and 696 are mounted upon the studs 692 and 693, respectively, for firmly hold-

ing the breaking head 651 in position upon the head support 631.

The alternate mandrel 701 (FIGURES 51 and 52) has a body portion 700 which is preferably formed from a single piece of material, such as steel, aluminum, plastic or the like, and which is substantially rectangular in shape. Said body portion has an elongated central opening 702 extending therethrough which serves to reduce the weight of the mandrel to minimize the friction between the mandrel and the carton when it is removed therefrom, and to provide a location for the carton positioning member 703.

The carton positioning member 703 (FIGURES 51 and 52) includes an elongated post 704, the lower end of which is slidably and removably received into the upper end of a post opening 706, which extends through the wall 714 defining the bottom end of the opening 702. The upper end of the post 704 has an upwardly opening recess 707 into which a pin 708 is slidably received. A spring 709 in the recess 707 resiliently resists downward movement of the pin 708 beyond a certain point within the recess 707. The upper end of the pin 708 is tapered upwardly for snug, removable reception into a tapered opening 712 in the wall 713 defining the upper end of the opening 702 therein. The "at rest" length of the post 704 and pin 708 is longer than the lengthwise distance between the wall 713 and the wall 714. Accordingly, it is necessary to move the pin 708 into the recess 707, against the contrary urging of the spring 709, in order to place the post 704 in its position of FIGURE 52.

A thumb screw 717 (FIGURE 53) is threadedly received into a threaded opening 718 which extends into the mandrel body 700 and communicates with the post opening 706 below the wall 714. The inner end of the screw 717 is tapered and engageable by the lower end of the post 704. Thus, movement of the thumb screw 717 into the post opening 706 will urge the post 704 upwardly.

The post 714 (FIGURE 51) has a plurality of spaced annular grooves 719. A flat, bifurcated stop 722 has a pair of legs 723 and 724 which are snugly receivable into diametrically opposite sides of each groove 719. The bifurcated stop 722 extends outwardly beyond the side walls of the mandrel 701 on opposite sides thereof when the post 704 is disposed in its FIGURE 52 position. Thus, downward movement of a carton 725 (FIGURE 51) is positively limited by engagement thereof with the ends of the stop 722. By removing the bifurcated stop 722 and placing it into another annular groove 719, the mandrel 701 can be quickly and easily converted to handle a carton of a different length. The post 704 is easily and quickly removable for thorough and sanitary cleaning of the mandrel.

Circuit diagram

The circuit diagram shown in FIGURE 43 discloses a starting switch 730 which closes to energize the coil 728 and thereby closes the self locking relay 729. The coil 728 also closes the relays 731, which connect the vacuum pump motor 732 and index table motor 733 to a source of electrical potential 734, such as a single-phase, 60 cycle, 220-volt outlet. In this particular embodiment, the transformer 736 converts the 220-volt input to a 110-volt output for the operating circuit of the machine. However, the heat 738 is connected across the 220 lines.

Circuit breakers 739 have their relays 741 in series with the starting switch 730 to open that line in case of a motor failure. Closure of the heater switch 742 closes the relay 743 and thereby energizes the coil 744 whereby the heater relay 746 is closed and the heater 738 becomes energized. The starting switch 730 includes terminals 747 which close to energize the coil 750 and thereby close the self-locking relay 755. The coil 750 also closes the normally open relay 749 and opens the normally closed relay 751. Thus, when the starting switch 730 is closed, the green lights 752 and 753 are illuminated and the red light 754 is extinguished.

The switch 756 is closed by the piston of the pressure cylinder 757 (FIGURE 44), which supports the heater 738, when said heater is in its raised position. The switches 758, 759 and 760 (FIGURE 43) are similarly closed by the operation of the pressure cylinder 763, unloading cylinder 764 and loading cylinder 765, respectively (FIGURE 44) when their pistons are moved into their raised positions.

Closure of the switches 756, 758, 759 and 760 energizes the coil 768 whereby the relay 762 is closed to energize the clutch coil 770. Thereafter, the carrier assembly 557 (FIGURE 42) is indexed for 90 degree one step of rotational movement. It will be noted that the switch 759 is mechanically coupled with terminals 769 in series with the solenoid 771. The terminals 769 are opened when the pick-up cylinder 761 is in its fully raised position. The solenoid 771 (FIGURE 44) controls the vacuum air into the suction cups of the head 772 on the unloading cylinder 764 which is part of the discharge mechanism 559 (FIGURE 42).

The switch 780 remains closed as long as the pick-up cylinder 761 (FIGURE 44) is not in its raised position. The switch 773 is actuated by the indexing movement of the carrier assembly 557, thereby energizing the coil 774 which closes the relays 775 and 776 and thereby energizes the coil 778. Energization of coil 778 closes relay 779 and thereby locks in the relay coil 778. The coil 778 also closes the relay 781, which operates the solenoid 783 (FIGURE 44) and effects a downward movement of the piston rod of the unloading cylinder 764. Accordingly, since the solenoid valve 771 places vacuum pressure on the suction cups 784 of the head 772, the downward movement of the piston in the cylinder 764 will result in the engagement and subsequent raising of a carton from the mandrel in the discharge station adjacent the discharge mechanism 559.

Energization of the relay coil 782 by closure of the relay 776 closes the normally open relay 786 whereby the solenoid 787 is operated to move the pistons of the heat cylinder 757 of the pressure cylinder 763 downwardly.

The normally closed switch 792 is in series with the normally open relay 791. The switch 788 is momentarily closed by the retracting or return stroke of the piston in the pick-up cylinder 761 (FIGURE 44), thereby energizing the coil 789 which closes the relay 791 and completes the series circuit through the switch 792. However, the switch 792 is opened, thereby de-energizing the coil 789, when the piston of the load cylinder 765 is in its fully down position.

Energization of the coil 789 also closes the relay 793 whereby the solenoids 794 and 795 are operated when the switch 797 is in its broken line position. Switch 797 is in its broken line position when the pick-up cylinder 761 is in its fully retracted position. The solenoid 794 (FIGURE 44) operates the unloading cylinder 764 and, at the same time, the top breaking cylinder 798 whereby the pistons of both cylinders are moved downwardly. When the piston on the pick-up cylinder 761 is in any position other than its fully retracted position, the switch 797 is in its solid line position whereby the solenoid 799 is energized, if the master pick-up switch 802 is closed. The normally closed relay 803 is opened by the closing of the starting switch 730, thereby extinguishing the red light 804.

The switch 606 is closed, thereby energizing the solenoid 607, whenever the crossbar 583 (FIGURE 47) moves into its lowered position at the lower ends of the slots 584 and 585. Energization of the solenoid 607 operates the pressure cylinder 597, whereby the slide plate 582 is moved rightwardly. The switch 606 is opened when the crossbar 583 returns to said uppermost position and the spring return on the solenoid 607 operates to reverse the flow of pressure fluid to the cylinder 597 whereby the slide plate 582 is moved leftwardly. Accordingly, it will be seen that the slide plate 582 cannot move rightwardly unless it is in its solid line power position of FIGURE 47

and it is moved leftwardly only when it is in its raised, broken line position.

The solenoids 783, 787, 771, 794, 795, 799 and 607 (FIGURE 43) are all preferably of the spring return-type whereby the valves associated therewith will reverse the flow of fluid to their cylinders when the solenoids are de-energized.

The pressure pad 806 (FIGURE 44) may be part of a pressure mechanism, such as the pressure mechanism 24 appearing in FIGURE 2. Said pressure pad 806 is connected by conduits 807 and 808 to a pair of panel guides 809 and 810 which are hollow, but are preferably shaped similar to the guide bars 171 and 172 appearing in FIGURE 4. Accordingly, a coolant, such as water, can be circulated through the panel guides 809 and 810 as well as the pressure pad 806 to facilitate sealing of the bottom panels on a carton 588 and to prevent scoring of said panels as they are bent downwardly by the guides 809 and 810 toward their bottom farming positions.

Although particular preferred embodiments of the invention have been disclosed herein for illustrative purposes, it will be understood that variations or modifications of such disclosures, which come within the scope of the appended claims, are fully contemplated.

What is claimed is:

1. In a machine for receiving an erected tubular carton blank and for forming an end wall on the erected tubular carton blank from closure panel means at one end thereof, the combination comprising:

a frame structure;

carrier means mounted on said frame structure for substantially horizontal movement around a substantially vertical axis;

a plurality of elongated mandrels having rectangular cross sections, there being at least two groups of mandrels of different sizes, the mandrels of one size being connected to and extending upwardly from said carrier means at uniform intervals around said vertical axis and extending parallel with said vertical axis for movement by said carrier means along a closed, substantially horizontal path around said vertical axis, an erected carton blank being snugly and slidably receivable onto each mandrel of said one size;

drive means operably associated with said carrier means for effecting step-by-step movement of said carrier means along said path, whereby each of the mandrels of one group is moved, one at a time, into and out of the carton-receiving position in said path;

mechanism mounted on said frame structure along said path for sequentially performing operations upon the closure panel means, whereby the end wall is formed on each erected carton blank while it is on a mandrel of said one size;

means connected to said carrier means for moving said carrier means a selected amount around said vertical axis, whereby the mandrels of one group are moved into the positions occupied by the mandrels of the other group;

means for effecting the operation of said drive means and said mechanism on said frame structure.

2. In a machine for receiving an erected tubular carton blank and preforming an end wall on the erected tubular carton blank from closure panel means at one end thereof, the combination comprising:

a frame structure;

carrier means mounted upon said frame structure for movement around a substantially vertical axis;

a first set of four spaced, vertical mandrels upon each of which an erected carton blank of one size is snugly and slidably receivable, said mandrels having substantially rectangular horizontal cross sections and being connected to said carrier means for movement thereby along a closed, substantially horizontal path passing around said vertical axis and through a carton-receiving position;

a second set of four vertical mandrels upon each of which an erected carton blank of another size is snugly and slidably receivable, each mandrel of said second set being located along said path between a pair of mandrels of said first set, the mandrels of said first set and of said second set being spaced at the same, uniform intervals along said path;

drive means operably associated with said carrier means for effecting step-by-step movement of said carrier means along said path whereby each of the mandrels in one of said first and second sets is moved, one at a time, into and out of said carton-receiving position in said path;

mechanisms mounted upon said frame structure at three spaced locations along said path and adjacent said mandrels for sequentially performing operations upon the closure panel means, whereby the end wall is formed on each erected carton blank while it is on one of said mandrels, the distance along said path between said locations being substantially equal to the distance between two mandrels of one of said sets, and one of said locations being at said carton-receiving position;

means connected to said carrier means for moving said carrier means a selected distance around said vertical axis, whereby the mandrels of one group are moved into the positions occupied by the mandrels of the other group; and

means for effecting the operation of said drive means and said mechanisms on said frame structure.

3. In a machine for receiving an erected tubular carton blank and for forming an end wall on the tubular carton blank from closure panel means at one end thereof, the combination comprising:

a frame structure;

driven means mounted upon said frame structure for rotational movement around a substantially vertical axis;

mandrel engaging means operably connected to said driven means for movement thereby around said vertical axis;

a plurality of rigid and elongated mandrels having rectangular cross-sectional shapes of uniform size throughout the length of each mandrel, said mandrels being rigidly connectible to said mandrel engaging means parallel with said vertical axis for movement thereby in a substantially horizontal direction along a circular path around said vertical axis, a first set of four of said mandrels being of one cross-sectional size and a second set of four of said mandrels being of another cross-sectional size, the mandrels of each set being connectible to said mandrel engaging means at substantially uniformly spaced intervals along said path;

drive means operably associated with said driven means for effecting intermittent, unidirectional movement of said mandrel engaging means along said circular path, whereby each of the mandrels in one of said sets of mandrels is moved, one at a time, into and out of a carton-receiving position in said path, each movement of said engaging means along said path effecting a movement of said mandrels a distance equal to the distance along said path between adjacent mandrels in said one set;

mechanisms mounted upon said frame structure at four spaced locations along said path for sequentially performing operations upon the closure panel means, whereby the end wall is formed on each erected carton blank while it is on one of the mandrels and then said carton is removed from the mandrel, the distance between said locations along said path being substantially equal to the distance along said path between two mandrels in said one set, and one of said locations being adjacent said carton-receiving position;

means connected to said carrier means for moving said

carrier means a selected distance around said vertical axis, whereby the mandrels of one group are moved into the positions occupied by the mandrels of the other group; and

means effecting the operation of said mechanisms on said frame structure.

4. The structure of claim 3 wherein said two sets of mandrels of different sizes are connected to said mandrel engaging means at uniformly spaced intervals along said path, each mandrel in said first set being disposed between two mandrels in said second set.

5. The structure of claim 3 including a third set of four mandrels having cross-sectional sizes larger than the cross-sectional sizes of the mandrels of said first and second sets, and each mandrel in said third set being sleevable upon a mandrel in one of said first and second sets.

6. In a machine for receiving a tubular carton blank, for holding said tubular carton blank in an erected condition and for forming a bottom wall on the erected tubular carton blank from closure panel means at one end thereof, the combination comprising:

a frame structure;
carrier means mounted on said frame structure for rotational movement around a substantially vertical axis;

a plurality of elongated mandrels extending parallel with said vertical axis and secured near one end of each to said carrier means at spaced intervals along a circular path concentric with said vertical axis, said mandrels having rectangular cross sections and said erected carton blanks being snugly and slidably receivable onto the other end of each of said mandrels; drive means operably associated with said carrier means for effecting intermittent, unidirectional movement of said carrier means along said path whereby each of said mandrels is advanced along said path into and out of a plurality of spaced stations including a carton receiving station;

a plurality of mechanisms mounted on said frame structure at locations along said path for sequentially performing operations upon each carton blank, whereby the bottom wall is formed from the closure panel means on each erected carton blank while it is on a mandrel, one of said mechanisms being provided at said carton receiving station so that one of said operations is performed upon said carton blank while it is on a mandrel in said carton receiving station; and means effecting the operation of said drive means and said mechanisms.

7. In a machine for receiving a tubular carton blank, for holding said tubular carton blank in an erected condition, for forming a bottom wall on the erected tubular carton blank from first closure panel means at one end thereof, and for prebreaking second closure panel means at the other end of said tubular carton blank, the combination comprising:

a frame structure;
carrier means mounted on said frame structure for rotational movement around a substantially vertical axis;

a plurality of elongated mandrels extending parallel with said vertical axis and secured near one end of each to said carrier means at spaced intervals along a circular path concentric with said vertical axis, said mandrels having rectangular cross sections and said erected carton blanks being snugly and slidably receivable over the other end of each of said mandrels;

drive means operably associated with said carrier means for effecting intermittent, unidirectional movement of said carrier means along said path whereby each of said mandrels is advanced along said path into and out of a plurality of spaced stations including a carton receiving station;

a plurality of mechanisms mounted on said frame structure at spaced locations along said path and adjacent

said stations for sequentially performing operations upon the first closure panel means of each carton blank, whereby the bottom wall is formed on each erected carton blank while it is on a mandrel, one of said operations being performed upon said first closure panel means of each carton blank while it is on a mandrel in said carton receiving station;

guide means on said frame structure for positioning a carton blank having a bottom wall thereon, and a device for prebreaking the second closure panel means thereof; and

means effecting the operation of said drive means, said mechanisms and said device.

8. The structure of claim 7 including:

a magazine for holding a plurality of flattened tubular carton blanks; and

erecting mechanism supported upon said frame structure adjacent said carton receiving station for engaging a carton blank in said magazine and for erecting said carton blank while moving same into a loading position adjacent the other end of a mandrel in said carton receiving station; and

wherein said mechanisms include a loading mechanism located adjacent said carton receiving station for moving the erected carton blank from its loading position onto a said mandrel in said carton receiving station, said loading mechanism including panel engaging elements for breaking the first closure panel means along fold lines therein when said erected carton is disposed upon a mandrel in said carton receiving station.

9. The structure of claim 7 wherein said mechanisms include heater means located at the first station along said path following the carton receiving station, said heater means including:

a support member mounted upon said frame structure for movement into and out of a position close to said first station;

a heater shell;

reciprocable means mounted upon said support member and connected to said shell for effecting movement of said shell into and out of a position telescoping said other end of a mandrel in said first station; and

control means for effecting movement of said support member when said shell is out of said telescoping position for a preselected period of time.

10. The structure of claim 9 including a pair of breaking arms;

power operated means mounted upon said frame structure adjacent said first station and connected to said arms for moving same toward and away from each other in substantially horizontal directions to engage and move together selected portions of the closure panel means of an erected carton blank on a mandrel in the first station while the shell is in a non-telescoping position with respect to such mandrel.

11. The structure of claim 7 including a pressure member and power means supported upon said frame structure and connected to said pressure member for moving same toward and away from a position of engagement with the other end of a mandrel located in the second station along said path following the carton receiving station, said pressure member including a removable pressure pad on the side of said pressure member engageable with the mandrel, and a coolant passageway connectible to a source of coolant; and

backing means mounted upon said frame structure and engageable with said carrier means adjacent said second station for minimizing movement of said carrier means in a direction parallel with said axis and away from said pressure member when said mandrel is engaged by said pressure member.

12. The structure of claim 7 wherein said mechanisms include a carton discharge mechanism located in the third

station along said path following said carton receiving station, said discharge mechanism comprising:

a discharge housing mounted upon said frame structure and extending radially outwardly of the path of movement of said mandrels;

carton gripping means located adjacent said housing; power operated means connected to said carton gripping means for moving same between a first position of engagement with the bottom wall of a carton on a mandrel disposed in said third station and a second position wherein said carton gripping means holds the carton away from said mandrel;

baffle means adjustably mounted upon said housing for directing a carton away from the carrier means; and ejection means for moving a carton, which is released by said carton gripping means when it is in said second position, into an upright position and along said baffle means.

13. The structure of claim 12, wherein said guide means

includes conveyor means for receiving from said discharge mechanism a carton in an upright position and having a bottom wall, and for advancing said upright carton into a location adjacent the device for prebreaking the second closure panel means on the carton, and thereafter advancing said carton away from said prebreaking device, said prebreaking device including a vertically reciprocable head support mounted upon said conveyor means and a prebreaking head mounted upon said head support for vertical movement toward and away from said conveyor means, the second closure panel means of said carton being slidably receivable into said prebreaking head for being bent thereby, the relative movement between the carton and said prebreaking head being sufficient to increase the pressure within said carton above ambient pressure and thereby urge the side walls of said carton outwardly against the inner walls of said prebreaking head.

14. The structure of claim 7 wherein each mandrel has a pair of lengthwise shallow recesses extending along two opposite side walls thereof and spaced from the lateral edges of said side walls;

wherein each mandrel has a slot extending transversely therethrough in a direction substantially parallel with said two side walls, said slot being elongated lengthwise of the mandrel so that it extends from a point near one end of the mandrel to a point near the other end thereof; and

each mandrel including post means removably supported within the slot of each mandrel and extending lengthwise of said mandrel, and a stop member removably connectible to said post within said slot and extending transversely of the post and beyond the lateral surfaces of the mandrels for the purpose of engaging the edge of a carton blank mounted upon said mandrel and thereby positioning said carton blank upon the mandrel.

15. In apparatus for removing cartons from mandrels on a machine for preforming said cartons, and for pre-breaking the closure panel means adapted to form the top walls of the preformed cartons, comprising:

gripping means for gripping cartons on the mandrels and removing same therefrom;

guide means for guiding the cartons released by the gripping means into an upright position with said closure panel means facing upwardly;

a conveyor for receiving said cartons from said guide means and moving them to a prebreak station; and prebreak mechanism at said prebreak station, said prebreak mechanism including a head movable with respect to said cartons for engaging said closure panel means and moving same with respect to the carton at said prebreak station.

16. An apparatus according to claim 15, in which said prebreak head includes a hollow member sleeveable over the upper end of the carton and having openings therethrough;

a plenum chamber surrounding said hollow member and alternately connectible to a source of positive pressure and a source of vacuum whereby said carton can be firmly held within and against the walls of said hollow member by vacuum in said chamber and said carton can be discharged from said hollow member by connecting said plenum chamber to said source of positive pressure;

and means within said hollow member for engaging said closure panel means and flexing same with respect to the rest of said carton.

17. In a machine for receiving an erected tubular carton blank and for forming an end wall on the erected tubular carton blank from closure panel means at one end thereof, the combination comprising:

a frame structure;

carrier means mounted on said frame structure for substantially horizontal movement around a substantially vertical axis;

a plurality of elongated mandrels having rectangular cross sections, there being at least two groups of mandrels of different sizes, the mandrels of the respective sizes being connected to and extending upwardly from said carrier means at uniform intervals around said vertical axis and extending parallel with said vertical axis for movement by said carrier means along a substantially circular and horizontal path around said vertical axis, an erected carton blank being snugly and slideably receivable onto said mandrels;

drive means operably associated with said carrier means for effecting step-by-step movement of said carrier means along said path and means for adjusting the drive means with respect to the carrier means so that the respective groups of mandrels can be alternatively positioned for movement into and out of a carton-receiving position whereby each of the mandrels of one group is moved, one at a time, into and out of the carton-receiving position in said path;

mechanism mounted on said frame structure along said path for sequentially performing operations upon the closure panel means, whereby the end wall is formed on each erected carton blank while it is on a mandrel; and

means for effecting the operation of said drive means and said mechanism on said frame structure.

18. In a machine for receiving an erected tubular carton blank and preforming an end wall on the erected tubular carton blank from closure panel means at one end thereof, the combination comprising:

a frame structure;

carrier means mounted upon said frame structure for movement around a substantially vertical axis; a first set of four spaced, upright mandrels upon each of which an erected carton blank of one size is snugly and slideably receivable, said mandrels having substantially rectangular horizontal cross sections and being connected to said carrier means for movement thereby along a closed, substantially horizontal path passing around said vertical axis and through a carton-receiving position;

a second set of four upright mandrels upon each of which an erected carton blank of another size is snugly and slideably receivable, each mandrel of said second set being located along said path between a pair of mandrels of said first set, the mandrels of said first set and of said second set being spaced at the same, uniform intervals along said path;

drive means operably associated with said carrier means for effecting step-by-step movement of said carrier means along said path and means for shifting the carrier means between two different driving connections with said drive means, each such connection positioning the mandrels of one set for movement into said carton-receiving position whereby each of the mandrels in one of said first and second sets can be moved, one at a time, into and out of said carton-receiving position in said path;

mechanisms mounted upon said frame structure at three spaced locations along said path and adjacent said mandrels for sequentially performing operations upon the closure panel means, whereby the end wall is formed on each erected carton blank while it is on one of said mandrels, the distance along said path between said locations being substantially equal to the distance between two mandrels of one of said sets, and one of said locations being at said carton-receiving position; and

means for effecting the operation of said drive means and said mechanisms on said frame structure.
